UNITED STATES PATENT OFFICE.

WILLIAM T. VARNEY, OF VANCOUVER, BRITISH COLUMBIA, CANADA.

VAGINAL WASHER.

Application filed December 14, 1922. Serial No. 606,878.

This invention relates to a device for irrigating or washing the vagina, the improvements being directed to the provision of means for dilating or expanding the vagina to enable the liquid, whether for simple washing or for the application of a medicament to obtain access to its inner surface.

The device is designed to be simple in construction and effective in use and such as may be readily cleansed and sterilized.

The invention is particularly described in the following specification, reference being made to the drawings by which it is accompanied, in which:

15 Fig. 1 is a vertical longitudinal section through the device.

Fig. 2 is an end view in the direction of the arrow 2 in Fig. 1.

20 Fig. 3 is a similar view when expanded.

25 Fig. 4, a longitudinal section showing a modification.

In these drawings 2 represents the central tube through which the washing liquid is delivered. The lower end of this tube has provision at 3 for connection to it of the flexible tube from a fountain or from a bulb pump, and the upper end has a stepped enlargement 4 terminating in a conoidal end 5 which has a series of small delivery apertures 6 around the conoidal part.

30 On this tube 2 is slidably mounted the hub of a ring guard 7 having four relatively narrow dilator members 8 projecting from it parallel to the axis of the tube 2 and extending beyond the conoidal end 4 thereof. The outer surfaces of these dilator members 8 are in cross section segments of a circle of the normal diameter of the vagina and their outer ends 9 are laterally enlarged and inwardly turned as at 10 to contact with one another and form a rounded end to the combined members. Between the connection of these dilator members to the ring are apertures 11 to provide exit for the washing fluid.

35 A contact 12 projects radially inward from the inner side of each dilator member immediately beyond the conoidal end 4 when the tube 2 is withdrawn, which members the conoidal end engages when it is endwise moved and expands the dilator members outward against their spring resistance.

40 The width of the dilator members is only such as to afford a comfortable contact with the wall of the vagina, leaving a space between each pair of members for the appli-

cation of the irrigating or washing liquid as delivered from the apertures 6 of the conoidal end 4.

45 If, as may be desirable, the dilator members 8 are made of a material not having sufficient strength or elasticity to withstand the flexure, they may, as shown in Fig. 4, be hinged at 13 to portions upwardly projecting from the ring guard 7, in which case 50 each dilator member is produced slightly beyond the hinge, as at 14, to contact with the stepped enlargement 4 of the central tube and retract the member 8 when the tube 2 is outwardly drawn.

55 It will be noticed that as the conoidal end of the tube 2 is endwise moved to engage and expand the dilator members 8, the liquid is also delivered toward the ends of these dilator members and effectively reaches the 50 upper end of the vagina adjacent the os or mouth of the womb.

60 I am aware that dilators have heretofore been used for ocular inspection of the vagina, but without provision for washing or 65 conveying a medicament to the wall thereof, while so expanded. Further, in all dilators with which I am acquainted, the dilator members are externally produced beyond their hinge connection and are expanded by 70 pressure applied to the produced ends. Such construction necessitates a more complicated appliance and a greater strength and weight of the dilator members, than 75 where, as in this case, the dilation is effected intermediate the ends of the dilator members by the enlarged inner end of the central stem through which the washing or medicated liquid is conveyed. Nor have any provided for endwise movement of the liquid 80 delivery while the vagina is expanded and contracted.

85 Having now particularly described my invention, I hereby declare that what I 80 claim as new and desire to be protected in 90 by Letters Patent, is:

95 1. A vaginal dilator, comprising a central tube having a conoidal end provided with discharge apertures adjacent the point thereof, and having provision at the other end for connection to a source of liquid supply, a member endwise movable on the tube, said member having a series of relatively narrow dilator members projecting from it substantially parallel to the axis of the tube, said members having inwardly curved 100 spoon-ends adapted to lie in contact when 105 110

the dilator members are not expanded, said dilator members having inwardly projecting contacts adapted to be engaged by said conoidal end when brought in contact therewith to expand the dilator members outwardly upon forward movement of said conoidal end, means for limiting the movement of said endwise movable member whereby when the dilator is expanded said conoidal end will lie always within the confines of the dilator members substantially as shown and described.

2. A vaginal dilator, comprising a central tube having a conoidal end provided with discharge apertures adjacent the point thereof, and having provision at the other end for connection to a source of liquid supply, a member endwise movable on the tube, said member having a series of relatively narrow dilator members projecting from it substantially parallel to the axis of the tube, said members having inwardly curved

spoon-ends adapted to lie in contact when the dilator members are not expanded, said dilator members having inwardly projecting contacts adapted to be engaged by said conoidal end when brought in contact therewith to expand the dilator members outwardly upon forward movement of said conoidal end, means for limiting the movement of said endwise movable member whereby when the dilator is expanded said conoidal end will lie always within the confines of the dilator members, said tube having a stepped enlargement adjacent said conoidal end, said dilator members comprising pivoting elements, said stepped enlargement adapted to engage said dilator members on return movement to move them on their pivots to contract the same, substantially as shown and described.

In testimony whereof I affix my signature.

WILLIAM T. VARNEY.
